CHARLES T. WESTLAKE, OF ST. LOUIS, MISSOURI, ASSIGNOR TO DAVIS LOCOMOTIVE WHEEL COMPANY, OF ST. LOUIS, MISSOURI, A CORPORATION OF DELAWARE.

LOCOMOTIVE BUFFER-BEAM

No. 854,131.

Specification of Letters Patent.

Patented May 21, 1907.

Application filed February 2, 1907. Serial No. 355,446.

To all whom it may concern:

Be it known that I, CHARLES T. WESTLAKE, a citizen of the United States, residing at St. Louis, in the State of Missouri, have invented a new and useful Improvement in Locomotive Buffer-Beams, of which the following is a specification.

My invention relates to a metallic buffer-beam or end sill for a locomotive or car under-frame, and has for its object to produce a buffer-beam having its members arranged to the best advantage for insuring the direct transmission therethrough of the buffing and other concussive stresses to the longitudinal beams or sills of the said frame, and thereby preventing fracture of adjacent parts of the buffer-beam and at the same time maintaining its maximum strength with the least amount of material.

20 The invention consists in features of novelty as hereinafter described and claimed, reference being had to the accompanying drawing forming part of this specification, whereon,

25 Figure 1, is a top plan of a preferable form of my improved buffer-beam; Fig. 2, a vertical transverse section thereof on line 2, 2, in Fig. 1; Fig. 3, a cross section through one of the inclined members of the beam on line 3, 3, in Fig. 1, and Fig. 4, an end elevation of the beam as seen from the right of Fig. 1; Fig. 5, a view partly in top plan, and partly in horizontal section, on line 5, 5, in Figs. 6 and 7, of a modified form of the buffer-beam, 30 and Figs. 6 and 7, vertical transverse sections thereof on lines 6, 6, and 7, 7, respectively in Fig. 5.

Like letters and numerals of reference denote like parts in all the figures.

40 Referring to Figs. 1, 2, 3, and 4, *a* represents my improved buffer-beam or end sill, which is preferably composed of cast steel integral throughout and practically I-shaped in cross section, having when assembled, its 45 flared members 1, and 2, vertically arranged, the rear or inside members 1 being adapted to bear against the ends of the longitudinal beams *b* of the engine frame (or sills of the car frame as the case may be) to 50 which the buffer-beam *a* is secured in the present case by bolts 3, which pass vertically through brackets 4, formed on the outer face of the rear member 1, and through the beams *b*, as shown, or in any other suitable

manner. The opposite or front member 2, 55 of the buffer-beam *a* is preferably parallel to the rear member 1, for a suitable distance on each side of the middle of the beam *a*, or longitudinal center of the engine or car frame, and thence inclined toward and united with 60 each end of the rear member 1, where the beam *a* is formed preferably with an inside and outside push pole pocket or concave recess 5. Through the horizontal web 6, which unites the rear and front members 1 65 and 2 together, are formed openings 7 and 7', the openings 7 being separated from each other at the middle of the beam *a* by a portion of the web 6, which is intersected at right angles by ribs 8 coinciding with the 70 longitudinal center of the frame and uniting with the rear and front members 1 and 2, to which, with the said portion of the web 6 they form a middle intermediate strut. Similarly, each opening 7 is separated from its 75 adjacent opening 7' by an inclined portion of the web 6 which is intersected at right angles by ribs 9, the ribs 9 uniting with the rear and front members 1 and 2, and forming with the said inclined portion of the web 6 80 an inclined strut thereto between the front member 2 and that portion of the rear member 1 immediately in front of the longitudinal frame beam *b*. To the outside face of the front member 2 of the beam *a* is fixed 85 the bracket 10 (indicated by dotted lines in Fig. 1) for the coupler. Or in lieu of the bracket 10, a draw-bar pocket adapted to receive a suitable draft-rigging may be substituted therefor.

90 By this construction, the buffing stress on the front member 2 of the beam *a* is transmitted by compression through the inclined struts 9, which consequently tend to spread at, and produce an opposing and equalizing tension of the rear member 1 between its supports or points of attachment to the longitudinal beams *b* or sills of the frame through which the resultant stress is transmitted. When pulling on the coupler through the 95 bracket 10, the stress on the front member 2 produces tension of the inclined struts 9 and a consequent opposing and equalizing compression of the rear member 1 between its 100 said supports. Furthermore, in applying pressure to the push pole pocket 5 at the end of the beam *a* as indicated by the arrows in Fig. 1, the resulting tension of the front 105

member 2 is equalized by an opposing compression of the rear member 1, and conversely, when pushing on the inside pocket 5. In other words, by the above construction, all the said members are "statically" arranged, so that a force acting on any member is balanced by an equal force on another member acting in an opposite direction.

In Figs. 5, 6, and 7, the buffer-beam a' in lieu of being I-shaped in cross section as before described, is box-shaped, having its top side solid throughout, and its bottom side formed with lighting openings 11, the struts 8' and 9', which unite the rear and front members 1' and 2' together, being similar to the struts 8 and 9 before described.

I am aware that beams of this class have been made of various shapes in cross section and general configuration, but with their component members arranged without regard to statical requirements to insure an equilibrium of forces therethrough.

What I claim as my invention and desire to secure by Letters Patent is:

The combination with the longitudinal 25 sills of a locomotive or car underframe, of a buffer-beam having a rear member adapted to bear against the ends of the said sills, a front member opposite to, and spaced apart from the rear member, a strut uniting the 30 said members on each side of the longitudinal center of the said frame, the said struts diverging from the front member to their junction with the rear member at points opposite to the said ends of the corresponding 35 sills, and means for fixing the buffer-beam to the said sills, substantially as described.

In testimony whereof I have hereunto signed my name to this specification in the presence of two subscribing witnesses.

CHARLES T. WESTLAKE.
